UNITED STATES PATENT OFFICE.

JOHN A. BAKER, OF LOS ANGELES, CALIFORNIA.

WELL PUMP.

Application filed March 24, 1923. Serial No. 627,298.

To all whom it may concern:

Be it known that I, JOHN A. BAKER, a citizen of the United States, residing at Los Angeles, county of Los Angeles, State of California, have invented new and useful Improvements in Well Pumps, of which the following is a specification.

This invention has to do with pumps of that variety ordinarily known as well pumps; although from the following specification and description of a typical form of device it will be readily understood that my present pump is not necessarily restricted to use in pumping wells, although that is the major use to which it is put.

There are many objects and corresponding features of accomplishment of the invention, as will be best understood from a consideration of the following description of a preferred and specific form of pump that embodies, and is illustrative of, the invention. Accordingly, I will not make any preliminary statement of the objects and features of the invention but will leave those to be gathered from the following detailed description of the device and of its features of operation.

Accordingly, I refer to the accompanying drawings, in which—

Fig. 1 is a vertical longitudinal section showing a preferred form of my improved pump;

Fig. 2 is an enlarged cross section on line 2—2 of Fig. 1; and

Fig. 3 is a longitudinal central section of the plunger portion of the pump.

In these drawings I show at 10 the stationary pump barrel that has upper and lower heads 11 and 12 adapted, respectively, to connect the pump barrel to the well tubing and to the pipe 13 that extends on down below the pump barrel proper. This pipe 13 carries at its lower end a member 14 having a seat 15 in which the standing valve 16 is seated. Below the standing valve there may also extend the usual suction pipe 17.

The heads 11 and 12 confine between them the sectional barrel liner that is made up of sections 18 preferably joined at their ends by the shouldered joints shown at 19. These joints keep the sections in proper alignment, so that the interior bores of the liner sections from a single smooth interior bore extending the whole length of the barrel liner. These sections are held together endwise by the heads 11 and 12; and they pref-

erably clear the inside of barrel 10 at all points, so that no irregularity of the interior of the barrel 10 will disturb the perfect alignment of the barrel liner.

The pump plunger is made up in a peculiar manner, so that a longitudinal pull on the plunger is first transmitted down through the interior part of the plunger to its lower end, and then upwardly from the lower end through the outer or lighter part of the plunger and its packings. The plunger has an interior hollow plunger body 20 to the upper end of which is attached the valve cage member 21. This valve cage member is preferably screwed onto the upper end of the plunger as shown at 22 and it confines between itself and the upper end of plunger body 20 the valve seat 23. The valve 24 plays in the cage above seat 23. The upper end of the valve cage member 21 is adapted for attachment to the pump rod 25. For instance, it is provided with a threaded pin 26 that engages the usual socket at the lower end of the pump rod. The pump rod thus acts directly on the valve cage member 21; which member forms, in effect, an upward extension of plunger body 20. The threaded connection at 22 is strong enough to withstand all strains to transmit the upward pull directly to the plunger body. The exterior surface of valve cage member 21, is, like that of the plunger body, cylindrical; and is of the same size as the exterior of the plunger body. At the lower end of the plunger body 20 is attached a lower wiper shoe 30, being threaded onto the plunger body as shown at 31 with threads of sufficient strength to transmit the pull from the plunger body to this wiper shoe. This wiper shoe has a downwardly extending petticoat 31^a with a relatively sharp lower edge that is adapted to wipe sand or any other accumulation from the interior wall of the barrel liner, and thus keep the barrel liner clean. Also this shoe is provided with a spider 32 that forms a support for an eye-bolt 33 to which a flexible connection 34 (shown in the form of a chain) is connected, the lower end of the flexible connector being attached at 35 to the upper end of a standing valve 16. The standing valve may be of any of the usual types; the only peculiarity I here illustrate is that the standing valve has an enlarged head or flange at its upper end as shown at 36, this flange having an external diameter very nearly as large as the internal

diameter of pipe 13, so that the small clearance at this point will more or less prevent sand from settling down around the standing valve. The velocity of the oil passing upwardly through the comparatively small clearance space also tends to carry the sand up away from the standing valve.

The wiper shoe 30 has an external diameter larger than plunger body 20; and the shoe is intended to fit closely, but slidably, in the internal bore of the barrel liner. At 10 this shoe has a shoulder upon which a body of expansive packing 41 rests. The shoulder 40 is, in effect, an annular abutment projecting from the internal body and is preferably inclined so that vertical compression of the packing will more readily cause its radial expansion. Then above the packing body 41, and mounted around plunger body 20, there is a plunger liner that is made up of a plurality of liner sections 42. These liner sections fit more or less closely to the exterior of the plunger body, and their ends may be joined on the diagonal or conical joint surfaces as shown at 43. The uppermost one of these plunger liner sections has at its upper end a conical end surface 44 on which another body of expansive packing 45 rests. On this upper body 15 of packing 45 the upper wiper shoe 46 rests, the lower end of this shoe also having a diagonal or conical surface adapted to cause, with the action of the upper end surface 44 of the plunger liner, radial expansion of packing 45 by virtue of longitudinal compression. The interior bore of shoe 46 at its upper end is tapered as shown at 46^a to make a relatively sharp edge at the upper end of the wiper shoe; and, further, the 20 upper end of valve cage 21 has a corresponding tapered expanded part 21^a that fits in the tapered bore 46^a and thus prevents the wiper shoe 46 from moving upwardly off the plunger. This interengagement between shoe 46 and the valve cage member is intended only to hold the various parts in place; it is not intended primarily for the purpose of expanding packings 41 and 45 except to obtain their initial expansion when the plunger is first put into the barrel. When the parts are assembled, the packing 41 may be first put in place against lower shoe 30, then the several plunger liner sections 42 are slipped into place, then packing 45 put into place and the shoe 46 put into place; the valve cage 21 being screwed down into place to hold upper shoe 46 and all the other parts in place. The upper and lower shoes form, in effect, extensions of the plunger liner; being of the same external diameter.

When the pump is in operation the upward pull of pump rod 25 is transmitted through valve cage 21 and plunger body 20 to the lower shoe 30. It will be understood from

the foregoing description that the packings and the plunger liner and the upper shoe 46 are supported from below on lower shoe 30. Pressure of the oil, standing in the tubing above the pump, pressing down on shoe 46, tends to move that shoe downwardly and to longitudinally compress packing 45 and tends likewise to move the plunger liner sections downwardly on the plunger body and to compress longitudinally the packing 41. Consequently, both packings are expanded radially directly in proportion to the amount of liquid pressure on the packings; and the packings are therefore kept in condition effectively to seal the pump, regardless of what the liquid pressure may be.

Furthermore, (and this action is true of the device regardless of whether expansible packings 41 and 45 are used) it will be seen that no longitudinal tension is put on the plunger liner. Whatever strain is put on the plunger liner is a strain of compression; and therefore the plunger liner, supported as it is at its lower end, may be made in sections rather than in a single long piece. It is therefore capable of being made more accurate as to both thickness and concentricity of its inner and outer surfaces; and is not at all subjected to those longitudinal strains that might in many instances strain the plunger out of its true and straight cylindrical form. And this last is true whether or not the liner is made in sections. Furthermore, the liner may be made to fit the plunger body somewhat loosely (to the extent, say, of an easy fit) so that any deviation from trueness in the body will not effect the trueness of the liner.

Having described a preferred form of my invention, I claim:

1. In a pump plunger adapted to be reciprocated through a barrel, an internal plunger body having a pump rod connection at its upper end, a non-expansible surrounding liner for the plunger having frictional engagement with the barrel and being supported on the plunger body at its lower end, said liner being of relatively easy fit and movable longitudinally on the body, and means at the upper end of the plunger body to limit upward movement of the liner on the body.

2. In a pump, a plunger made up of an internal plunger body having a pump rod connection at its upper end, and a surrounding liner for the plunger supported on the plunger body at its lower end, said liner being composed of a plurality of end-wise abutting and non-expansible liner sections, said sections being of relatively easy fit and movable longitudinally on the body; and means at the upper end of the plunger body to limit upward movement of the liner on the body.

3. In a pump, a plunger comprising an

- internal body adapted at its upper end for connection with a pump rod, the body having an exterior upwardly facing shoulder near its lower end, an expansive packing 5 resting on said shoulder, a plunger liner surrounding the body and resting at the lower end on said packing, said liner being movable longitudinally on the body.
4. In a pump, a plunger comprising an internal body adapted at its upper end for connection with a pump rod, the body having an exterior upwardly facing shoulder near its lower end, an expansive packing resting on said shoulder, a plunger liner 10 surrounding the body and resting at the lower end on said packing, said liner being movable longitudinally on the body; another expansive packing surrounding the body and resting on the upper end of the liner, and a shoe surrounding the body above and resting on the second mentioned packing.
5. In a pump, a plunger having an internal body with a shoe at its lower end 15 presenting an upwardly facing shoulder external of the plunger body, and a plunger liner surrounding the plunger body and resting at its lower end on said shoulder, said shoe having a downwardly extending petticoat with a relatively sharp lower edge to wipe sand or the like off the wall of a barrel in which the plunger operates.
6. In a pump, a plunger having an internal plunger body with a shoe at its lower 20 end, said shoe presenting an upwardly facing shoulder external of the body, an expansive packing surrounding the body and resting on said shoulder, an exterior plunger liner surrounding the body and resting 25 on its lower end on said packing, and means to limit upward movement of the liner on the plunger body.
7. In a pump, a plunger having an internal plunger body with a shoe at its lower 30 end, said shoe presenting an upwardly facing shoulder external of the body, an expansive packing surrounding the body and resting on said shoulder, an exterior plunger liner surrounding the body and resting 35 on its lower end on said packing, a valve cage mounted at the upper end of the interior plunger body, and means to limit upward movement of the liner on the plunger body embodying a shoulder on the valve cage.
8. In a pump, a plunger having an internal plunger body with a shoe at its lower 40 end, said shoe presenting an upwardly facing shoulder external of the body, an expansive packing surrounding the body and resting 45 on said shoulder, an exterior plunger liner surrounding the body and resting on its lower end on said packing, an upper expansive packing surrounding the plunger body and resting on the upper end of 50 the plunger liner, an upper shoe surround-
- ing the plunger body and resting on said upper packing, said shoe having a relatively sharp upper edge, and a valve cage mounted on the upper end of the plunger body and engaging said upper shoe to limit its 55 upward movement with reference to the plunger body.
9. In a pump, a plunger adapted to be reciprocated through a barrel and made up of an internal plunger body having a pump 60 rod connection at its upper end, a loosely surrounding, non-expansile liner for the body, said liner having frictional engagement with the barrel; and means at the upper and lower end of the plunger body 65 adapted to coact with the liner in a manner to limit relative longitudinal movement of the liner and plunger body.
10. In a pump, a plunger adapted to be reciprocated through a body of liquid with- 70 in a barrel, said plunger including an internal plunger body, an abutment on the lower end of the plunger body, a surrounding liner for the plunger and longitudinally movable with respect thereto, said liner having frictional engagement with the barrel 75 and comprising a plurality of liner sections in end to end relation, and expansile packing between the ends of two adjacent liner sections; the lowermost liner section being 80 limited in its downward movement by coaction with said abutment, and the upper end of the uppermost liner section being 85 exposed to the liquid above it.
11. In a pump, a plunger adapted to be reciprocated through a body of liquid with- 90 in a barrel, said plunger including an internal plunger body, an abutment on the lower end of the plunger body, a surrounding liner for the plunger and longitudinally movable with respect thereto, said liner having frictional engagement with the barrel 95 and being composed of a plurality of liner sections in end to end relation, expansile packing between the ends of two adjacent liner sections; the lowermost liner section being 100 limited in its downward movement by coaction with said abutment, and the upper end of the uppermost liner section being 105 exposed to the liquid above it.
12. In a pump, a plunger made up of an internal plunger body, a valve cage mounted at the upper end of the body, and a surrounding liner for the plunger supported on the plunger body near its lower end and extending upwardly about said valve cage.
13. In a pump, a plunger made up of an internal plunger body, a valve cage mounted at the upper end of the body and having a pump rod connection, a surrounding liner for the plunger supported on the plunger body near its lower end and extending up- 120 wardly about said valve cage, and coacting 125
- 65 130

means on the valve cage and liner to limit upward movement of the liner on the plunger body.

14. In a pump, a plunger made up of an internal plunger body, a valve cage mounted at the upper end of the body and having a pump rod connection, a surrounding liner for the plunger supported on the plunger body near its lower end and extending upwardly about said valve cage, and coacting means on the valve cage and liner to limit upward movement of the liner on the plunger body, said means comprising complementary tapered portions on the exterior of the valve cage and on the interior of the liner.

15. In a pump, a plunger adapted to be reciprocated through a barrel and having an internal plunger body, an abutment on the lower end of the plunger, an expansible packing surrounding the plunger body and resting on the abutment, and a plunger liner surrounding the plunger body and resting on the packing, said liner being longitudinally movable on the body and frictionally

engaging the pump barrel whereby, during upward movement of the plunger, the liner moves downward relative to the body in a manner to longitudinally compress and radially expand the packing.

16. In a pump, a plunger adapted to be reciprocated through a body of liquid, said plunger including an internal body adapted at its upper end for connection with a pump rod, a surrounding liner for the plunger supported on the plunger body at its lower end, said liner being movable longitudinally on the body, an expansible packing surrounding the body and in contact with the peripheral face thereof, said packing resting on the upper end of the liner, and a rigid shoe surrounding the body above and resting on the packing, said shoe being movable longitudinally on the body and the upper edge of said shoe being exposed to the liquid above it.

In witness that I claim the foregoing I have hereunto subscribed my name this 10th day of March, 1923.

JOHN A. BAKER.
